UNITED STATES PATENT OFFICE.

WILLIAM C. OSTERHOLM, OF OAK PARK, ILLINOIS, ASSIGNOR TO WILCOX PRODUCTS CORPORATION, OF SAGINAW, MICHIGAN, A CORPORATION OF MICHIGAN.

VALVE TAPPET AND METHOD OF FORMING THE SAME.

Application filed April 21, 1924. Serial No. 708,048.

The invention relates to valve lifters or tappets and has for its objects; first, reduction in the cost of manufacture; second, the obtaining of a light durable structure; 5 third, various other advantages as herein-after set forth.

In the drawings:

Figure 1 illustrates the blank from which the tappet head is formed;

10 Figures 2 and 3 are cross sections showing successive steps in the forming of the head;

Figure 4 is an elevation of the blank from which the stem is formed;

15 Figure 5 is a stem formed from the blank;

Figure 6 is an enlarged section illustrating the manner of securing the stem to the head;

20 Figures 7 and 8 are sections showing modified constructions of stem;

Figure 9 is a section through the stem and head showing another modification;

25 Figures 10 and 11 are sections showing successive steps in the manufacture of the construction of Figure 9.

It is the primary object of the invention to separately form the head and stem of the tappet, this permitting both of economy in the use of material and the selection of 30 qualities best suited for the respective parts. In the manufacture of tappets it is usual to form the same of single blanks which may be either forged, cast or formed in various ways. The various operations re-

35 quired in the finishing of these blanks are such as to involve a considerable cost in manufacture, and the fact that the structure is all of one material precludes the selection of special qualities for different portions 40 thereof. For instance, the head, which is subjected to the wear of the cam, needs a hardened bearing surface, while the stem is stronger and better if left comparatively soft. The difference in hardness may be secured by suitably controlled heat treatment, 45 but this adds to the complexity and cost of manufacture.

Heretofore certain constructions of tappets have been made from separate blanks, 50 but such structures for various reasons have not proven altogether satisfactory and difficulty is experienced in securely uniting the head of the stem. With my improved struc-

ture this difficulty is entirely eliminated and the resulting structure is superior to those 55 formed from the single blank.

As shown in Figures 1 to 6, the method of manufacturing my improved tappet is as follows: A round disk blank of sheet metal A is fashioned, preferably by a coining 60 press, to form a recess B, as shown in Figure 2. The annular walls of this recess are undercut, as shown in Figure 3, and the face of the recess is preferably curved, as shown, for the purpose hereinafter described. The 65 blank may be formed of selected material and after fashioning may be given suitable heat treatment to secure the proper degree of hardness.

The stem may be formed in various ways, 70 but as shown in Figure 4 the blank D is a suitable length of round bar metal. This blank is then bored to form apertures of different diameters at the opposite ends, the smaller aperture E being threaded to receive the usual adjustment screw. This end of the blank may also be pressed or otherwise fashioned into a polygonal form to produce a wrench hold. The larger bore F is of such a diameter as to reduce the 75 walls to the required thickness. The end of the tube is then flared, as shown at G, by pressing in suitable dies, or by other means, so as to form an oblique flange of a diameter slightly less than the diameter of the 80 recess B.

The head and stem are united by endwise pressure, which results in turning the oblique flange G into a plane substantially perpendicular to the axis of the stem and thereby expanding the diameter so as to force the outer edge against the undercut annular wall into interlocking engagement therewith. This interlocking is facilitated by the angular movement of the flange G which expands the lower portion thereof to a greater 90 diameter than the upper portion conforming to the shape of the wall. Also, by curving the bottom of the recess as shown at H, the flange of the stem will be conformed thereto 95 without forming a sharp bend. Still another advantageous effect is that the inward pressure of the annular wall C, which resists the expansion of the flange G, will force the adjacent portion of the tube slightly inward, 100 resulting in a clearance groove I. Thus when

the stem is subsequently ground or machined for engagement with the guide bearing, this clearance groove will avoid necessity of grinding or machining immediately adjacent to the head.

5 The structure formed as just described is one where there will be no tendency for the head to separate from the stem as these parts are firmly interlocked. Furthermore, there 10 is a constant outward tension on the flange G, due to the resiliency of the metal and the fact that the adjacent portion of the tube has been slightly contracted in diameter during the pressing operation. The chamber 15 within the stem may be used as a lubricant container and I have therefore fashioned the central portion of the recess of cup form, as shown at J, with a central aperture K for feeding the lubricant directly 20 onto the cam.

As has been stated, the stem may be formed in various ways, such for instance as by any of the usual methods of drawing a tube from a sheet metal blank. During 25 this drawing operation the flared flange at the end of the blank is easily formed so as to be ready for engagement with a head in the manner previously described. Where, however, the blank is made from sheet metal, 30 the walls are of a substantially uniform thickness and it may be necessary to provide a bushing for the threaded end. This bushing L may be formed as shown in Figure 7 with a peripheral groove M into which the 35 tube is pressed by rolling or other suitable means, effecting the interlocking engagement. Figure 8 shows a cupped bushing L' for receiving the push rod of overhead valves, said bushing being similarly locked to the stem.

40 In Figures 9, 10 and 11 a further modification is shown wherein a tube of uniform diameter is expanded by endwise pressure to engage and interlock with an oblique annular slot N in the head. With this 45 construction the head O may first be formed as shown in Figure 10 with a conical face P surrounded by a flange Q parallel to the axis. The flange Q is then compressed and 50 forced inward into parallelism with the conical face P to produce the oblique slot N.

With all of the various modifications the 55 stem is interlocked with the head by the expansion thereof due to endwise pressure. Also this operation is performed after the completion, including the heat treatment, of the head so that there is no necessity of any further heat treatment or any operation which might tend to loosen the joint.

60 When the flaring end portion of the stem is pressed into a plane perpendicular to the axis, there is some danger of concentrating the stresses at the bend and overstraining the metal. Such an effect I have avoided 65 by first forming the flaring portion, as

shown specifically in Figure 5. It will be noted that as thus formed the portion immediately adjacent to the cylindrical portion of the stem is initially bent to approximately the plane perpendicular to the axis, 70 while the outer portion is oblique to the axis. With such a form the pressure applied to expand the stem into the head will only react on the flaring outer portion thereof and will not concentrate any bending stress at the angle between the cylindrical part and the flange; also, as the metal is chiefly in tension, it will be drawn without fracture. Still further, the portion 75 adjacent to the lower surface of the flange will be expanded to a greater extent than the upper surface thereof so as to fill the undercut portion of the recess in the head.

80 What I claim as my invention is:

1. The method of manufacturing tappets comprising the separate forming of a head member and a tubular stem member, said stem member having an annular end portion which is relatively oblique to a surface on said head member and said head member being undercut adjacent to said surface, and applying endwise pressure to said members to turn the end portion of said stem member and to force the same into interlocking engagement with the undercut portion of said head member.

2. The method of manufacturing tappets comprising the separate forming of a head member and a tubular stem member, said head member being provided with an undercut portion and a surface adjacent thereto which is relatively oblique to an annular end portion of said stem member, and applying endwise pressure to said members to turn the end of said stem member by the relatively 105 oblique portion of said head member and into interlocking engagement with the undercut portion thereof.

3. The method of manufacturing tappets comprising the separate forming of a head member and a tubular stem member, said head member being provided with an annular radially outward undercut portion, and a surface adjacent thereto which is relatively oblique to the annular end portion of said stem member, and applying endwise pressure to said members to outwardly bend the end portion of said stem member and to force the same into interlocking engagement with the annular undercut portion.

4. The method of manufacturing tappets comprising the separate forming of a head member and a tubular stem member, said head member being provided with an annular radially outwardly undercut portion and said stem member with an outwardly flaring annular end portion relatively oblique to the surface of said head member, and applying endwise pressure to said members to bend said flaring portion into parallelism with the 130

adjacent surface of said head and to thereby expand the same into interlocking engagement with said undercut portion.

5. The method of manufacturing tappets comprising the separate forming of a disk head and a tubular stem, said head being provided with an annular radially outwardly undercut portion and said stem with an outwardly flared annular end portion non-parallel to the adjacent surface of said head, and applying endwise pressure to said members to bend the end portion of said stem into parallelism with said head and thereby to peripherally interlock the same with said undercut portion.

6. The method of manufacturing tappets comprising the separate fashioning of a disk head member and a tubular stem member, said head member being provided with an annular radially outwardly undercut shoulder and a curved surface adjacent thereto, said stem being provided with a flaring annular end portion non-parallel to said curved portion on said head, and applying endwise pressure to said members to bend the flaring portion of said stem into parallelism with the curved portion of said head and to thereby peripherally expand the stem into interlocking engagement with said undercut shoulder.

7. The method of manufacturing tappets comprising the separate forming of a head member and a tubular stem member, said stem member being fashioned with a flaring annular end portion which in its outer part is more oblique to the axis of the stem than in the part immediately adjacent to the stem, said head being provided with an annular undercut portion, and applying end pressure to said members to bend the oblique portion of said stem and to peripherally expand the same into interlocking engagement with the undercut portion of said head.

8. The method of manufacturing tappets comprising the separate forming of a head member and a tubular stem member, said stem member being fashioned with a flaring annular end portion which adjacent to the body portion thereof is substantially in a plane perpendicular to the axis and is more oblique to the axis in its outer portion, said head being provided with an annular undercut shoulder of sufficient minimum diameter to receive the flaring portion of said stem and in applying endwise pressure to said members to bend the oblique portion of said stem substantially into a plane perpendicular to the axis and thereby force the same into interlocking engagement with said annular undercut shoulder.

9. The method of manufacturing tappets comprising the separate forming of a head member and a tubular stem member, said stem member being fashioned with walls of greater thickness at one end thereof and with

a flaring annular portion at the opposite end thereof and said head being provided with an undercut annular shoulder of a minimum diameter sufficient to receive said flaring portion, and in applying end pressure to said members to peripherally expand said flaring portion of the stem and to force the same into interlocking engagement with said annular undercut portion of the head.

10. A tappet comprising a one piece head member recessed to form a bottom surface and an annular undercut shoulder, and a tubular stem member provided with a flaring end portion engaging said recess and interlocked with said undercut shoulder, said flaring end portion also having its lower surface contacting for its entire length with the bottom surface of said recess.

11. A tappet comprising a head member recessed to form an annular shoulder, and a tubular stem member provided with an annular flange at one end thereof extending substantially in a plane perpendicular to the axis and interlocked with said annular shoulder.

12. A tappet comprising a head recessed to form an annular shoulder and with a curved surface tangent to the bottom of said recess and a tubular stem having an annular flange at one end thereof rounded to lie against said curved surface of the head and with an outer portion substantially in a plane perpendicular to the axis of the stem and interlocked with said shoulder.

13. A tappet comprising a head recessed to form a bottom surface and an annular undercut shoulder, and a tubular stem having an annular flange extending substantially in a plane perpendicular to the axis of the stem, said flange having its lower surface engaging the bottom surface of said recess and having its outer annular edge interlocked with said undercut shoulder.

14. A tappet comprising a head having an annular recess forming a radially outwardly undercut shoulder and a tubular stem having an annular flange at one end thereof lying substantially in a plane perpendicular to the axis and interlocked with said undercut shoulder, the portion adjacent to said flange being of slightly less radius than the tubular portion.

15. A tappet comprising a head recessed to form an annular radially undercut shoulder with an inwardly extending curved surface tangent to the bottom of the recess and a tubular stem provided with an annular flange extending substantially in a plane perpendicular to the axis with its periphery interlocked with said undercut shoulder and the portion intermediate said peripheral portion and the body portion curved to fit the curve of said head and reinforced thereby.

16. A tappet comprising a disk head re-

- cessed to form an annular undercut shoulder with an inwardly extending curved surface tangent to the bottom of the recess and a central concave surface having an aperture centrally thereof, a tubular stem provided with an annular flange at one end thereof extending substantially in a plane perpendicular to the axis and peripherally interlocked with said undercut shoulder, said flange being rounded as it merges into the body of the tube to fit the curved surface of said head and the central recess draining the lubricant within the stem towards said central aperture.
17. A tappet comprising a disk head recessed to form an annular shoulder and a tubular stem having thickened walls at one end thereof and a polygonal exterior, the opposite end of said stem being provided with an annular flange extending substantially in a plane perpendicular to the axis of the stem and interlocked with said annu-

lar shoulder, the portion of said stem immediately adjacent to said flange being pressed radially inward to form a slight 25 groove.

18. The method of manufacturing valve tappets comprising the separate forming of a disk head and a tubular stem, said head being recessed to form an annular undercut shoulder and said stem being provided at one end with an annular flaring portion initially oblique to the axis of the stem, and in applying endwise pressure to said members to bend said flaring portion substantially into a plane perpendicular to the axis of the stem, thereby peripherally expanding the same into engagement with said undercut recess, the lower portion being expanded 40 to a greater extent than the upper portion to fill the undercut of the recess.

In testimony whereof I affix my signature.

WILLIAM C. OSTERHOLM.
